UNITED STATES PATENT OFFICE.

JOHN O. CARREY, OF ST. LOUIS, MISSOURI.

PROCESS OF MAKING GAS.

1,115,392.

Specification of Letters Patent. Patented Oct. 27, 1914.

Application filed July 28, 1913. Serial No. 781,398.

To all whom it may concern:

Be it known that I, JOHN O. CARREY, a citizen of the United States, residing at St. Louis, Missouri, have invented a certain new and useful Improvement in Processes of Making Gas, of which the following is a full, clear, and exact description, such as will enable others skilled in the art to which it appertains to make and use the same, reference being had to the accompanying drawings, forming part of this specification, in which—

Figure 1 is a vertical sectional view taken through the center of an apparatus particularly adapted for carrying out my improved process. Fig. 2 is a horizontal section taken through the lower portion of an apparatus particularly designed for carrying out my improved process. Figs. 3 and 4 are perspective views of rotary grate bars, such as are utilized in the apparatus. Fig. 5 is a detail elevational view of the means employed for imparting partial rotary movement to the grate bars.

My invention relates to a new and useful process of making gas, the principal object of my invention being to produce by a comparatively simple and easily practised continuous method, clean or comparatively pure producer gas from bituminous coal in a single chamber.

Heretofore, in the manufacture of producer gas it has generally been the practice to use two chambers, one for distilling the coal or separating the volatile elements therefrom, and the other chamber, which is heated to a comparatively high degree, being used for the fixing or the forming into permanent gas of the volatile elements liberated from the charge in the first chamber.

A further object of my invention is to burn coal to produce gas, the combustion of which produces heat to distil from a superimposed body of coal, volatile elements which, together with air, are forced through an incandescent portion of the bed of burning coal to eliminate from said volatile elements, and air all moisture or heavy hydrocarbon, thereby producing a fixed or permanent gas adapted for a variety of uses, and particularly in gas engines and the like.

The apparatus shown in the accompanying drawings, and hereinafter described, is particularly designed for practising my improved method, but it will be readily under-

stood that this apparatus may be varied slightly in details of construction and in size without departing from the spirit of my invention.

In the construction of the apparatus shown, 10 designates an outer shell or wall preferably formed of metal and provided with a lining 11 of fire brick or analogous material. This lining is extended inward at the upper end and formed in the center thereof is an opening 12, which, while the apparatus is in use, is closed and which is adapted to receive a suitable hopper utilized for charging the apparatus.

The construction just described provides a hollow cylindrical body, the same being supported a suitable distance above the ground upon a metal frame work 13. Located on the ground below the cylindrical body just described, is an ash pit 14 formed of brick or concrete and arranged in the bottom of the chamber in said ash pit and extending outwardly therefrom is a spiral conveyer 15 which is for the purpose of removing ashes and waste material which drops into the chamber within the ash pit.

Mounted to rotate freely upon ball-bearings 16 positioned on top of the ash pit is a ring 17 with which is formed integral a series of inwardly projecting radially disposed arms 18, the inner ends of which are formed integral with a centrally arranged hub 19. Formed integral with the alternate ones of these arms 18 are upwardly projecting lugs or brackets 20 which serve as bearings for rotary grate bars hereinafter described, and formed between the arms 18 are openings 21 through which gas and air is forced upward through the rotary grate and the incandescent material thereon.

Arranged on the upper outer edge of the ash pit is a trough 22 which contains water and projecting downwardly thereinto is a continuous wall or plate 23 which is carried by the ring 17, and thus a water seal is formed between the top of the ash pit and the lower portion of the rotary producer section. Positioned on top of the ring 17 is a ring 24 preferably constructed of fire clay or analogous material, and seated in the outer portion of this ring is a metallic ring 25 which is channel shape in cross section.

Carried by the ring 17 and inclosing the ring 24 is a vertically disposed wall 26 preferably formed of metal and which is in

direct vertical alinement with the wall or shell 10, and arranged within this wall 26 is a lining 27^a preferably of fire brick which is in direct vertical alinement with the lining 11.

5 The wall 26 and its lining terminates immediate beneath the cylindrical body formed by the wall or shell 10, and lining 11. Carried by the upper edge of the wall 26 is a trough 27 which contains water and carried by the lower edge of the wall or shell 10 is a depending flange or wall 28 which projects into the trough 27, thereby forming a water seal between the lower movable part 10 of the producer and the upper fixed part thereof.

10 Rotatable grate bars 29, which are preferably noncircular in cross section, are arranged immediately above the openings 21 20 between the arms 18, said grate bars being carried by spindles 30, the inner ends of which are journaled for rotation in suitable bearings formed in the upper end of the hub 19. The outer ends of these spindles 30 25 project through the rings 24 and 25 and fixed on the outer ends of said spindles within the channel shaped ring 25 are disks 31 each being provided on its outer face with a series of outwardly projecting pins 32.

30 The inner portions of the grate bars 29 are enlarged as designated by 29^a and these enlarged portions practically fill the space between the lugs or bearings 20 and the hub 19. A series of rotary grate bars 33 which 35 are comparatively shorter than the grate bars 29 are alternately arranged between the grate bars 29 and said grate bars 33 are carried on spindles 34, the inner ends of which are journaled in the lugs or bearings 20. The outer portions of these spindles 40 pass through the rings 24 and 25 and their outer ends are provided with disks which are in every way similar to the disks 31.

45 Arranged upon a suitable arm or support 35 which is fixed to the frame work 13 is a depending triangular lug 36 which is positioned directly in the path of travel of the upper ones of the pins 32 which project from the disks 31, thus as the lower 50 portion of the producer rotates the upper one of the pins 32 strikes against the lug 36 and as a result, the disks, spindles, and grate bars carried thereby are rotated approximately one-third of a complete revolution.

55 Positioned on the outer face of the wall 26 is a continuous rack 37 and meshing therewith is a worm 38, the latter being formed on a shaft 39 which is driven in any suitable manner. This worm meshing with 60 the teeth of the rack 37 operates the lower portion of the producer and the rotary grate bars carried thereon. Positioned in the hub 19 and projecting upwardly through the chamber within the lower portion of the 65 producer is a post 39, the top of which ter-

minates in the same horizontal plane with the top of the wall 26, and its lining.

Arranged in the lower portion of the upper fixed part of the producer is a diametrically arranged transversely extending pipe 40 70 which is filled with water during the operation of the apparatus, and positioned upon said pipe is the lower end of an inclined wall 41 of fire brick or analogous material, the upper end of which terminates against the inner face of the lining 11, thereby dividing the space within the upper fixed portion of the apparatus into two chambers, one of which A is above and in front of the inclined wall 41 and the other B being behind or beneath said inclined wall. Suitable struts 42 of fire brick are arranged between the lining 11 and the inclined wall 41.

75 The post 39 in addition to serving as a covering for the bearings in which the spindles 30 and 34 operate, serves as a central support for that portion of the bed of fuel which is carried around with the rotating lower portion of the furnace, and said post is extended upward a sufficient distance to form a support for the pipe 40 in case the charge of material within the chamber A is sufficient to depress the central portion of said pipe, although, under normal conditions, the pipe does not touch the post. In case the pipe does bear upon the post during the rotation of the latter, the resulting friction is insufficient to retard the rotary movement of said post.

80 A pipe 43 leads from the upper portion 90 of the chamber B for the purpose of conveying the pure or fixed gases from the producer to the gasometer or to the point of use. Located adjacent to the producer is an exhaust fan 44 and leading thereto from the upper portion of the chamber A is a pipe 45. Leading from this exhaust fan 95 partially around the lower portion of the producer on the side below the chamber B is a pipe 46 from which leads inwardly 100 through the wall of the ash pit a series of branch pipes 47, the same being provided with elongated nozzles 48 which lie immediately beneath the arms 18, which project inwardly from the ring 17, and said nozzles 105 are provided with long narrow jet openings 49. Corresponding nozzles 50 provided with elongated jet openings 51 are alternately arranged between the nozzles 48, said nozzles 50 being connected to branch pipes 110 115 52, which lead through the wall of the ash pit 14 and connect to an air pipe 53 which latter leads partially around the lower portion of the producer beneath the pipe 46, and said air pipe being connected to a pressure blower 54.

120 It will be understood that the nozzles 48 and 50 are positioned only beneath that portion of the grate which is below the chamber B, and thus the volatilized carbonaceous 125

material drawn from the upper portion of chamber A, and the air, will be discharged upwardly through that portion of the bed of fuel which is directly beneath chamber B, and thus maintaining this portion of the bed of fuel in a high state of incandescence.

In practising my improved process with the apparatus herein shown and described, bituminous coal is fed into the chamber A through the opening 12 in the top of the producer, and combustion of said coal takes place on the rotating grate within the movable portion of the producer, which movable portion is rotated by the engagement of the worm 38 with the continuous rack 37. Simultaneously with the rotary movement of the lower portion of the producer the grate bars 29 and 33 are successively rotated by the engagement of the uppermost one of the pins 32 with the lug 36, and this rotation of the grate bars overcomes any tendency of the burning fuel to form clinker and as said fuel is completely burned the action of the rotating grate bars causes the resulting ashes to drop downward through the openings 21 between the arms 18 and pass into the chamber within the ash pit from whence said ashes are removed by means of the spiral conveyor 15.

By rotating the lower section in which the fuel is located it will be readily understood that the hottest portion of the fire will be upon that portion of the grate beneath the chamber B for the reason that by the time the fuel has been carried around to this point, said fuel has been practically consumed and the discharge of air upwardly through this particular portion of the bed of fuel for maintaining the same in an incandescent state.

As the exhaust fan 44 is operated the gaseous products from the burning fuel on the grate which is below the chamber A will be drawn upward through said chamber, thence through pipe 45 to the exhaust fan, from thence the volatile carbonaceous material, which is gas, carrying a certain amount of condensable matter in the form of tar and moisture, will be forced through pipe 46, from thence through branch pipes 47 through the nozzles 48, from which it will be discharged through the elongated jet openings 49, and thus be forced upward through the grate and through the bed of incandescent fuel located on that portion of the grate beneath the chamber B. Simultaneously with this action air is forced through pipe 53 by the pressure blower 54 which air passes through branch pipes 52, nozzles 50 and discharges therefrom through jet openings 51 upwardly through the grate. Thus volatilized carbonaceous material in gaseous form together with a certain amount of air, is forced upward through the incandescent bed of material on that portion of

the grate beneath the chamber B, and in thus passing through said incandescent bed, the heavy hydrocarbons are volatilized and as a result a fixed or permanent gas entirely freed of all condensable matter will issue from the producer through pipe 43.

Where gas is produced in ordinary bituminous coal producers there is a certain amount of tar and free hydrocarbons, and heretofore, it has been the practice to use two separate chambers or producers in the manufacture of a gas wholly freed of heavy hydrocarbons and the like, but by my improved process, it is possible to produce a permanent or fixed gas in one vessel or chamber.

One of the principal features of my improved process is that it can be operated continuously for as long as the producer is charged and the exhaust fan and pressure blower operated the pure fixed gas will be delivered ready for use through the discharge pipe 43.

An apparatus for practising my improved process is comparatively simple, can be easily and cheaply installed, and while in operation continuously produces a clean permanent gas entirely freed of all condensable matter and particularly adapted for a variety of uses.

I claim:

1. The herein-described process of making gas which consists in blasting a portion of the lower portion of the body of carbonaceous material by forcing air upwardly through the same whereby that portion of the carbonaceous material is maintained at a state of incandescence, continuously moving the body of the lower portion of the carbonaceous material whereby the burning portion is shifted away from the point of combustion and other portions brought thereto, simultaneously distilling the volatile elements from the upper portion of the carbonaceous material by radiated heat, withdrawing from the upper portion of the distillation zone the volatile elements, conveying said volatile elements to a point beneath the incandescent bed of material, and forcing said volatile elements upwardly through the entire body of incandescent material to convert said volatile elements into a fixed or permanent gas.

2. The herein-described process of making gas which consists in blasting a portion of the lower portion of the body of carbonaceous material by forcing air upwardly through the same whereby that portion of the carbonaceous material is maintained at a state of incandescence, continuously moving the body of the lower portion of the carbonaceous material whereby the burning portion is shifted away from the point of combustion and other portions brought thereto, simultaneously distilling the volatile elements from the upper portion of the carbonaceous ma-

- terial by radiated heat, withdrawing the volatile elements from a point above the zone of distillation, conveying said volatile elements to a point wholly beneath the incandescent bed of carbonaceous material and discharging said volatile elements at separated points upwardly through the incandescent bed of material to convert said volatile elements into a fixed or permanent gas.
- 10 3. The herein-described process of making gas which consists in blasting a portion of the lower portion of the body of carbonaceous material by forcing air upwardly through the same whereby that portion of the carbonaceous material is maintained at a state of incandescence, continuously moving the body of the lower portion of the carbonaceous material whereby the burning portion is shifted away from the point of 20 combustion and other portions brought thereto, simultaneously distilling the volatile elements from the upper portion of the carbonaceous material by radiated heat, withdrawing the volatile elements from a point above the zone of distillation, conveying the volatile elements to a point wholly beneath the body of incandescent carbonaceous material, and discharging said volatile elements upwardly into the incandescent body of material at points between the points of discharge of air into said incandescent body, whereby said volatile elements are converted into a fixed or permanent gas. 25
- 15 In testimony whereof I hereunto affix my signature in the presence of two witnesses, 30 this 19th day of July, 1913.
- JOHN O. CARREY.
